UNITED STATES PATENT OFFICE.

EDWARD M. HEYLMAN, OF SOUTH BEND, INDIANA, ASSIGNOR TO OLIVER CHILLED PLOW WORKS, OF SOUTH BEND, INDIANA.

PLOW.

1,386,868.

Specification of Letters Patent. Patented Aug. 9, 1921.

Application filed February 7, 1919. Serial No. 275,583.

To all whom it may concern:

Be it known that I, EDWARD M. HEYLMAN, a citizen of the United States, and a resident of South Bend, in the county of St. Joseph and State of Indiana, have invented certain new and useful Improvements in Plows; and I do hereby declare the following to be a full, clear, and exact description of the invention, such as will enable others skilled in the art 10 to which it appertains to make and use the same.

This invention relates to improvements in plows and more particularly to such as are equipped with power lift mechanism as illustrated in an application filed by me even date herewith and designated by Serial No. 275,582,—one object of my present invention being to provide simple and efficient means for adjusting the plow for depth of plowing 20 and for leveling, independently of the power-lift means and without interference with the operation of latter to raise the plow to its full height.

A further object is to provide adjusting devices which shall act as limiting means to control the depth at which the plow bases shall enter the ground, without permanent attachment to the axle of the plow structure.

A further object is to so construct depth 30 adjusting means for a plow structure having crank axles, that the same will engage the cranks in close proximity to the wheel-ends of said cranks and thus prevent springing or straining of the axle.

A further object is to provide adjusting 35 means for a plow having crank axle members for the land and furrow wheels which may be operated to adjust said axle members independently of each other without permanent connection therewith.

A further object is to provide an improved construction of axle comprising two members so connected that one member may be adjusted independently of the other to facilitate the leveling of the plow structure.

With these and other objects in view, the invention consists in certain novel features of construction and combinations of parts as hereinafter set forth and pointed out in 50 the claims.

In the accompanying drawings; Figure 1 is a plan view of a plow structure embodying my improvements; Fig. 2 is an elevation of one side of the structure; Fig. 3 is an

elevation showing a portion of the other 55 side of the structure; Fig. 4 is a detail view of the bracket 9; Fig. 5 is a detail view of the bracket 10, and Fig 6 is a detail view of the coupling member 19.

In the present instance I have shown a 60 plow structure comprising two beams 1—2 having standard portions 3—4 at their rear ends. and to these standards, plow bases 5—6 are secured. The beams are suitably spaced apart and connected by front and 65 rear braces 7 and 8,—said beams and braces thus forming a plow or beam frame.

Brackets 9 and 10 are secured to the respective beams, 1 and 2 and these brackets are formed with toothed segments 11 and 12 70 respectively, for a purpose hereinafter explained.

An axle 13 is mounted in hubs 14—15 on the respective brackets 9 and 10 and its horizontal portion is disposed under the respective beams 1, 2 so as to extend transversely thereof and from one to the other. At one end, the axle 13 is provided with a crank-arm 16 and at the free end of the latter, a spindle 17 is provided to receive the hub of a 80 land wheel 18. The other end of the axle 13 (at the furrow side of the plow structure) enters a coupling member 19, the latter being clamped to said axle 13 by means of bolts 20 passing through lugs 21, and said coupling member is also connected with the axle 13 by means of a key 22 shown in Figs. 3 and 6. The coupling member 19 is made with a bearing 23 for the pivotal mounting 85 of an arm 24 at one end of an axle member 90 or crank 25,—the latter being provided at its free end with a spindle 26 which enters the hub of a furrow wheel 27. The coupling member 19 is formed with a flaring arm or extension 28 having flanges 29—30 at its upper and lower edges between which the axle member 25 passes. It will be seen that by means of the coupling member 19, the two axle members 13 and 25 are connected together in such manner that one can move 95 relatively to the other,—and that the flanged extension will serve to limit the independent movements of the furrow-wheel axle member 25; that the upper flange 29 will engage the furrow-wheel axle member 25 and force the 100 furrow wheel back so that it will aline with the land wheel when the plow has been raised by means of power lift mechanism

which coöperates with the land-wheel axle member 13, as disclosed in my copending application, and that the lower flange 30 of said coupling member arm will prevent the furrow wheel from "kicking back" under the pivot of the axle member 25 when the furrow wheel strikes a high or low place in the field.

A hand lever 31 is pivotally mounted on 10 the hub 14^a of the bracket 9 and provided with a suitable detent to engage the toothed segment 11. This lever is provided at its pivoted end with a forwardly projecting arm 32 carrying a roller 33, the latter being 15 disposed over the crank 16 of axle member 13 near the forward end of said crank when the plow is in normal working position, said crank 16 being at that time, in an approximately horizontal position, as shown in 20 Fig. 2. A balance spring 31^a is connected at one end to the lever 31 and its other end is connected, by a link 31^b with the bracket 9 at 31^c.

A hand lever 34 is mounted upon the 25 bracket 10 at 35 (Fig. 5) and is provided with a suitable detent to engage the toothed segment 12,—said lever being provided at its pivoted end with a forwardly projecting arm 36 having a pin or boss 37 disposed over 30 the axle member 25 near the forward end thereof from which the spindle of the furrow wheel projects. A balance spring 34^a is connected at one end to the lever 34 and the other end of this spring is connected by 35 a link 34^b with an arm 34^c on the bracket 10, By locating the pin or boss 37 of the arm 36 near the forward end of the furrow wheel axle 25 when the furrow wheel is in working position, the springing effect of the axle will 40 be reduced to a minimum, thus overcoming such springing of the axle as is liable to occur with constructions where the operating levers are applied to the upper pivotal portions of crank axles.

45 It will be observed that the hand levers 31 and 34 are not permanently connected with the axle members, but the parts 33 and 37 carried by these levers serve as stops for the axle members, and by locating such stops 50 over the axle members near the wheel-ends of the latter, the springing (above referred to) of the axle members by reason of the heavy downward pull on the wheels by the suction of the plow bases when passing 55 through heavy spots in the field, will be prevented, and the changing of the adjustment of the plow for depth of plowing by reason of springing of axle cranks, will be avoided.

With the use of the jointed axle member, 60 and adjusting levers, the movement of the front furrow wheel axle independently of the land wheel axle, allows the raising of the front furrow wheel on the frame so that the bottom of the wheel will be above the 65 base of the front plow when opening up of

a land, or making the first furrow, and when the front furrow wheel is adjusted low on the frame so the bottom of the wheel is on a line with the bottom of the front base when running in the bottom of the furrow, this 70 movement allows of the adjusting of the land wheel up and down without imparting movement to the front furrow wheel for leveling the plow at different depths. To increase the depth, the furrow wheel may be 75 raised and the plow leveled with the land wheel and to decrease the depth, the furrow wheel may be lowered and the plow leveled with the land wheel, and when the furrow is the correct depth, the lower side of the front 80 furrow wheel should be on a line with the bottom of the front base.

With the construction and arrangement of adjusting levers and the parts with which they coöperate, as hereinbefore described, 85 power-lift mechanism can be employed which can be operated to raise the plow structure to its full height regardless of the particular depth adjustment at which said levers may be set.

90 The rear end of the end of the plow structure is supported on a rear follower or furrow wheel 38, the axle 39 of which, is mounted in a bearing sleeve 40, the latter being pivotally attached to a bracket 41 secured to the plow standard 3. The bearing sleeve 40 is provided with an arm 42 normally engaging one end of a lever 43, which is held in adjusted position by a screw 44. A slack link 45 is connected with the upper end of 95 the lever 43 and this link is connected by a rod 46 with an arm 47 secured to and projecting upwardly from the axle member 13, so that when the latter is turned in a forward direction, motion will be transmitted 100 through the rod 46, slack link 45 and lever 48 to the bearing sleeve 40 to raise the rear end of the plow structure on the rear furrow wheel,—such operation being effected by 105 the turning of the axle member 13 when the plow structure is raised by the power-lift mechanism disclosed in my copending application.

110 Having fully described my invention what I claim as new and desire to secure by Letters-Patent, is:—

115 1. In a plow structure, the combination with a plow frame and carrying wheels at respective sides thereof, of crank axle members connecting said frame with the wheels, and adjusting levers mounted on the frame and having parts disposed over and coöperable directly with the cranked portions of the respective crank axle members and free from the same, whereby the plow structure 120 may be adjusted for depth of plowing.

125 2. In a plow structure, the combination with a beam frame, carrying wheels, and crank axle members mounted on said frame and having spindle portions mounted, re- 130

- spectively, in the hub of said wheels, of adjustable levers mounted on the frame and each having a part disposed over the crank of one of said axle members and between 5 the ends of said crank and adjacent to the wheel-end of said crank, said part of each lever being free from the adjacent axle crank and coöperable directly therewith to effect depth adjustment.
- 10 3. In a plow structure, the combination with a beam frame, a plow base carried thereby, and carrying wheels, at respective sides of the frame, of two crank axle members connecting the frame with the wheels, 15 and two levers mounted on the frame, said levers having parts disposed over and free from the cranks of said axle members near their wheel-ends and coöperable directly with said cranks to adjust the frame and the 20 plow base carried thereby.
4. In a plow structure, the combination with a beam frame, a plow base carried thereby, and land and furrow wheels, of a crank axle member mounted on the frame 25 and having a part mounted in the hub of the land wheel, a coupling member free from the frame and secured to the land-wheel axle member near one end thereof and carried thereby, a furrow wheel axle member 30 pivotally connected with said coupling member, and means coöperable with said axle members to adjust the plow.
5. In a plow structure, the combination with a beam frame, a plow base carried 35 thereby, and land and furrow wheels, of two crank axle members pivotally connected together, one only of said crank axle members being mounted directly on the frame, and means coöperable directly with and free 40 from the crank axle members and operable independently to adjust the plow.
6. In a plow structure, the combination with a beam frame, a plow base carried thereby, and land and furrow wheels, of 45 land and furrow wheel crank axle members, the land wheel crank axle member mounted on the beam frame, a coupling member secured to the land wheel crank axle member and having a flaring arm provided with upper and lower flanges, said furrow wheel 50 crank axle member having a pivotal mounting in said coupling member and movable between the flanges on the flaring arm there-
- of, and adjusting means coöperable with the cranks of said crank-axle members. 55
7. In a plow structure, the combination with a beam frame, a plow base carried thereby, and land and furrow wheels, of a crank axle member mounted on the frame and in the hub of the land wheel, a crank-axle member mounted in the hub of the furrow wheel, a coupling member secured to the land-wheel axle-member said furrow-wheel axle-member having pivotal mounting in said coupling member, means on said coupling member to limit the movement of the furrow-wheel axle member relatively to the land-wheel axle member, and adjusting means coöperable with said crank-axle members. 60
8. In a plow structure, the combination with a beam frame, carrying wheels, and a crank axle, of an adjusting lever mounted on the frame and having an arm coöperable directly with but free from a crank of the 75 crank axle, a balancing spring secured at one end to said lever, and means connecting said spring with the frame.
9. In a plow structure, the combination with a frame, a plow base carried thereby, 80 land and furrow wheels, and crank axle members for said wheels, said crank axle members being relatively movable, of a lever pivoted on the frame, an arm projecting from said lever and provided with a part 85 disposed over and free from the crank of the furrow-wheel axle member and coöperable therewith, and means for locking said lever.
10. In a plow structure, the combination with a frame, a plow base carried thereby, 90 and carrying wheels, of two axle members for said wheels, said axle members pivotally connected together and one only of said axle members being mounted on the plow frame, levers mounted on the frame and having 95 parts disposed over and free from the cranks of the respective crank axle members and coöperable with the same, and locking means for said levers.

In testimony whereof, I have signed this 100 specification in the presence of two subscribing witnesses.

EDWARD M. HEYLMAN.
